Primary Examiner — Jasmine Mlinarcik(74) *Attorney, Agent, or Firm* — Dunlap Bennett & Ludwig, PLLC(57) **CLAIM**

The ornamental design for a bow tie, as shown and described.

DESCRIPTION

FIG. 1 is a perspective view of a bow tie, showing my new design;

FIG. 2 is a right-side elevation view thereof;

FIG. 3 is a left-side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a perspective view of the bow tie, shown in use. The broken lines showing toys in FIG. 8 depicts environmental subject matter that forms no part of the claimed design.

The shading applied along the wings of the bow tie depict a transparent appearance.

1 Claim, 5 Drawing Sheets(56)
